(57) **CLAIM**

The ornamental design for a corner feeder, as shown and described.

DESCRIPTION

FIG. 1 is a perspective view showing the top, rear, and left side of the corner feeder and showing a support tab and support ring at each of the three corners;

FIG. 2 is a front view thereof;

FIG. 3 is a left side view thereof;

FIG. 4 is right side view thereof;

FIG. 5 is a top view thereof;

FIG. 6 is a bottom view thereof;

FIG. 7 is a rear view thereof; and,

FIG. 8 is another perspective view showing the bottom, front and left side.

The broken lines illustrate portions of the corner feeder that form no part of the claimed design.

1 Claim, 8 Drawing Sheets
